Fig. 6

Fig. 7

FIG. 1 is a front elevational view of a touch control panel for the control console of a domestic cooking appliance, showing my new design and shown mounted on a free-standing range;

FIG. 2 is a front elevational view of the touch control panel;

FIG. 3 is a top plan view thereof;

FIG. 4 is a transverse sectional view taken along lines 4-4 of FIG. 2 looking in the direction of the arrows;

FIG. 5 is a front elevational view of another embodiment of the touch control panel designed for a wall oven;

FIG. 6 is a top plan view thereof;

FIG. 7 is a transverse sectional view taken along lines 7-7 of FIG. 5.

The portion of a free-standing range shown in broken lines in FIG. 1 is for illustrative purposes only and forms no part of the claimed design.

I claim:

The ornamental design for a touch control panel for the control console of a domestic cooking appliance, as shown and described.
